COMPOSITION CONTAINING PENICILLIN
AND AN ADJUVANT OF THE GENERAL
FORMULA $R_1CH_2SO_2NHR_2COOH$ James M. Sprague, Drexel Hill, and Karl H. Beyer,
Jr., Bala Cynwyd, Pa., assignors to Sharp &
Dohme, Incorporated, Philadelphia, Pa., a cor-
poration of MarylandNo Drawing. Original applications September 5,
1946, Serial No. 695,040, and July 15, 1947, Se-
rial No. 761,153. Divided and this application
June 15, 1950, Serial No. 168,541

2 Claims. (Cl. 167—55)

1.

This invention relates to new compositions which are valuable for use in the administration of penicillin to provide an increase in the blood plasma penicillin concentration with a given penicillin dosage level, thereby permitting the use of smaller quantities of penicillin for providing a given blood level, or the provision of very high penicillin blood levels, or permitting the less frequent administration of penicillin while maintaining a penicillin blood level adequate for bactericidal or bacteriostatic purposes.

Penicillin today is a well established therapeutic agent used in the treatment of various bacterial, in particular, coccus infections. For internal use it is commonly administered intravenously, intramuscularly, orally, sublingually, subcutaneously, or rectally. Where high blood levels are required, as in the treatment of acute infections or sub-acute bacterial endocarditis, or where it is desired to establish a high blood level promptly, intravenous administration, and at times administration by continuous venoclysis is used. Frequently administration is by intramuscular injection, in which case, to maintain blood levels adequate for therapeutic purposes, injections are ordinarily given at 3 to 4 hour intervals where the menstruum is aqueous, and at less frequent intervals where the menstruum is oleaginous. Oral administration is also used to a considerable extent, but with oral administration dosages of about four times those required with intramuscular injection are required to establish comparable blood levels and administration is required about as frequently, the cost thus being substantially greater.

The major cause of the difficulties involved in attempting to maintain adequate or high penicillin blood levels follows from the rapid excretion of penicillin by the kidneys. Penicillin is removed, in the kidney, from the blood stream, not only by glomerular filtration but also by selective excretion by the renal tubules, and its removal from the blood stream on passage of the blood through the renal system is almost quantitative. For this reason, frequent administration is necessary to keep any measurable amount of penicillin in the blood stream, and where a high blood level is required it is necessary to use enormous dosages, and to administer penicillin by continuous venoclysis. Thus to maintain blood levels of the order of 10 to 20 units of penicillin per cc. of plasma may require the administration of over 10,000,000 units per day of penicillin, and even with administration at this rate, it is not possible to obtain blood levels as high

as may be desirable in many instances without using accessory agents, to be referred to. The maintenance of high blood levels of penicillin is, in many cases, important because, while relatively low concentrations, for example, 0.06 unit per cc., are extremely effective in many cases, in other cases, where, for example, the organisms are resistant to penicillin, much higher concentrations are required to combat the organisms, and the provision of the high concentration of penicillin in the blood stream permits the treatment of infections which are resistant to penicillin in the low concentrations which are obtained when it is administered orally or by intramuscular injection, as is the case with the organism which causes sub-acute bacterial endocarditis, *Streptococcus viridans*.

The problem presented by the rapid elimination of penicillin has been recognized, and various proposals have been made to overcome it. One such proposal involves the administration of penicillin in suspension in an oleaginous material, for example, soya bean or other fatty oil, or a mixture of such an oil with beeswax, the mixture being administered by intramuscular injection. Oleaginous material is absorbed much less rapidly than an aqueous material similarly injected, and therefore the penicillin is disseminated in the blood stream more slowly and some penicillin remains in the blood stream over a longer period of time than when an aqueous menstruum is used. While this proposal is effective in prolonging the time interval between injections, it is subject to the disadvantage that the penicillin is still excreted almost quantitatively from the blood which passes through the renal system, and therefore does not permit the maintenance of high blood levels nor does it permit the use of smaller quantities of penicillin for the establishment of a given blood level, the effect being merely to permit the injection of a very large quantity of penicillin at one time and provide for its slower and more prolonged absorption into the blood stream.

Penicillin is removed by the kidneys both by glomerular filtration and excretion by the tubules, and apparently is not reabsorbed by the tubules. With a normally functioning kidney about 19% of a crystalloid such as penicillin or any of the other crystalloid materials in the plasma water, is removed by the glomeruli from the blood which flows through the renal system. This removal is considered to be of the nature of a filtration, with the plasma water and its solutes being removed by the glomeruli and passed to

the tubules. Most of the water removed by this glomerular filtration and the crystalloids dissolved therein are returned to the blood stream by reabsorption during passage of the filtrate through the lumen of the tubule to maintain the physiological economy of the system, but certain materials, of which penicillin is one, are not so reabsorbed, and therefore whatever penicillin is removed by glomerular filtration is excreted. The epithelial cells of the tubules also serve to remove certain materials from the blood stream as well as to reabsorb selectively substances from the glomerular filtrate and return them to the blood stream. Materials which are so excreted by the tubules are presumably not reabsorbed. The extent to which tubular excretion takes place differs with various materials. Penicillin appears to be almost quantitatively excreted from the blood by the epithelial cells of the tubules, at least within plasma concentrations which have been explored. The result of this is that the rate of excretion of penicillin from the blood stream is approximately five times the rate of excretion of materials which are excreted by glomerular filtration alone, the tubular excretion accounting for about 80 (81) % and the glomeruli about 20 (19) %; and substantially all of the penicillin in the blood which passes through the renal system is removed in a single circulation through the kidneys. It is for this reason that it is necessary to administer penicillin frequently to maintain any measurable concentration in the blood stream and to administer it in extraordinarily large quantities where it is desired to maintain a blood level in excess of about one unit per cc.

The removal of penicillin and other crystalloids from the blood stream by the glomeruli is thought to be a physical phenomenon involving the simple filtration of plasma water and its crystalloid solutes, as distinguished from protein materials, from the blood stream. The selective excretion by the tubules is thought to be a metabolic process, with the epithelial cells of the tubes functioning physiologically to remove the penicillin from the plasma and transport it to the filtrate in the tubule.

The second proposal which has been made to provide for the reduction in the rate of excretion of penicillin has been to use, in conjunction with the penicillin, a material which, like penicillin, is selectively excreted by the tubules, with the thought that by imposing a sufficient load on the tubule excretion mechanism, it could not function to remove from the blood stream all of the penicillin and all of the added agent, so that the removal of penicillin would be reduced. By having the ratio of the added agent to the penicillin sufficiently large, this concept provides for a substantial reduction in the rate of excretion of penicillin by the tubules and thus slows down the removal of penicillin to a substantial extent. Various agents which are removed by tubular excretion, including the diethanolamine salt of 3,5-diiodo-4-pyridone-N-acetic acid and hippuric acid, or derivatives or precursors thereof, have been proposed or used for this purpose and their use has resulted in a reduction in the rate of penicillin excreted and provided for higher plasma concentrations or longer duration of the action from a given dose of penicillin. Such agents do not, however, seem to afford a solution to the problem of value except in extreme cases, because as the reduction in the rate of penicillin excretion is a reflection of the degree of overloading of the tubules with materials which they

function to remove from the blood, it is necessary to maintain a very high concentration of the agent in the blood stream to afford a favorable partition ratio between the agent and the penicillin and, in addition, because the agents are themselves rapidly removed from the blood stream, it is necessary to administer them in large quantities to maintain the necessary high plasma concentrations. Thus, while p-aminohippuric acid is effective to reduce the rate of penicillin excretion, its threshold concentration, where an inhibiting effect can be noted, is something over 10 mg. per 100 cc. and substantial inhibition of tubular excretion of penicillin is only obtained at plasma concentrations of 40 to 60 mg. per 100 cc. To maintain such levels, in view of the rapid excretion of the material, it is necessary to use 130 to 250 grams of material per day by intravenous injection. With such materials as the diethanolamine salt of 3,5-diiodo-4-pyridone-N-acetic acid and p-aminohippuric acid the quantity which must be introduced into the blood stream is so large, both because of the high plasma concentrations required and the high rate of excretion involved, that intravenous administration is required, the materials not being well absorbed from the gastro-intestinal tract.

The new compositions of the invention are composite products including penicillin and an adjuvant of the general formula

in which R_1 is selected from the class consisting of hydrocarbon and dialkyl ether radicals having a total of from 3 to 7 carbon atoms, phenyl, aminophenyl, nitrophenyl, halophenyl, and benzyl, and R_2 is selected from the class consisting of benzene and thiazole. The adjuvant constituent of the composition operates to block the removal of penicillin from the blood stream by the tubules of the kidneys without itself being excreted to any substantial extent by the tubules. The action of the adjuvant appears to involve an interference with the normal functioning of the transport mechanism of the epithelial cells of the tubules such that they do not function to remove the penicillin from the blood stream. The new compositions are effective in eliminating or radically reducing tubular excretion of penicillin at plasma concentrations of around 10 mg. of adjuvant per 100 cc. of plasma, which is about the threshold value for agents such as p-amino hippuric acid which inhibit tubular penicillin excretion by competition for the available tubular excretion capacity. By the use of the new compositions, the tubular excretion of penicillin is reduced to almost zero, so that the actual elimination of penicillin from the blood stream becomes that substantially which results from glomerular filtration, that is, about one-fifth the normal rate (ignoring plasma binding).

In particular, the invention comprises a composite product including penicillin and one of the adjuvants listed below:

1. 4'-carbethoxy-phenylmethanesulfonanilide.
2. 4'-carboxy-phenylmethanesulfonanilide.
3. Mono - sodium - 4'-carboxy-phenylmethanesulfonanilide.
4. Disodium - 4'-carboxy-phenylmethanesulfonanilide.
5. N - methyl-4'-carboxy-phenylmethanesulfonanilide.
6. 2 - chloro-4'-carbethoxy-phenylmethanesulfonanilide.

7. 2 - chloro-4' - carboxy-phenylmethanesulfonanilide.
8. 4-nitro-4' - carbethoxy-phenylmethanesulfonanilide.
9. 4-nitro - 4' - carboxy-phenylmethanesulfonanilide.
10. 4 - amino-4' - carbethoxy-phenylmethanesulfonanilide.
11. 4 - amino-4' - carboxy-phenylmethanesulfonanilide.
12. 3-nitro-4' - carbethoxy-phenylmethanesulfonanilide.
13. 3 - amino-4' - carbethoxy-phenylmethanesulfonanilide.
14. 4 - carbethoxy- β -phenylethanesulfonanilide.
15. 4' - carboxy- β -phenylethanesulfonanilide.
16. 4 - amino-4' - carboxy-phenylmethanesulfonanilide hydrochloride.
17. p-Carbethoxy-1-pentanesulfonanilide.
18. p-Carboxy-1-pentanesulfonanilide.
19. p-Carboxy-1-heptanesulfonanilide.
20. 3' - carboxy-phenylmethanesulfonanilide.
21. 2' - carbomethoxy-phenylmethanesulfonanilide.
22. 2 - phenylmethanesulfonamido-4-carbethoxythiazole.
23. 2 - phenylmethanesulfonamido - 4 - carboxythiazole.
24. 2 - phenylmethanesulfonamido-4-methyl-5-carbethoxymethylthiazole.
25. 2 - phenylmethanesulfonamido-4-methyl-5-carboxymethylthiazole.
26. 4' - carbomethoxy-phenylmethanesulfonanilide.
27. p-Carboxy-1-butanesulfonanilide.
28. p-Carboxy-2-methyl-1-propanesulfonanilide.
29. p-Carboxy-3-methyl-1-butanesulfonanilide.
30. p-Carboxy-1-hexanesulfonanilide.
31. p-Carboxy-2-ethoxy-1-ethanesulfonanilide.

The preparation of these effective adjuvants is described in detail in copending patent applications Serial No. 695,040, filed September 5, 1946, now abandoned, and Serial No. 761,153, filed July 15, 1947, now U. S. Patent No. 2,531,367.

In general, the quantity of the adjuvant which is included with the penicillin in the composite product is from about 8 to about 24 grams per day, which is quite comparable to dosages commonly used with the sulfonamides and is adequate to suppress the rate of penicillin excretion to an extent such that the blood levels with a given dosage of penicillin administered orally or intramuscularly in aqueous solution will be increased to as much as four times or more the level obtained without the use of any adjuvant and will permit either the use of a very much smaller quantity of penicillin to provide a given blood level or the provision of higher penicillin blood levels as compared with those obtainable with the administration of penicillin by the routes ordinarily used today. In general, quantities of penicillin ranging from 1500 to 7500 units per gram of a compound of the invention are used with advantage, and in administering penicillin along with the selected adjuvant, due account should be taken of the property of the adjuvant of markedly increasing the amount of penicillin in the blood stream when a given quantity of it is administered.

In any event, the quantity of the selected adjuvant included should be such as to provide a concentration in the blood stream adequate to block substantially the excretory mechanism of the tubules. Most of the adjuvants exert a maxi-

mum effect with blood plasma concentrations of about 5 to 15 mg. per 100 cc., obtainable at dosage levels of about 8 to 24 grams per day orally and somewhat less than this intravenously.

- 5 When the composite product including the adjuvant and penicillin is intended for oral administration, tablets containing one or more of the adjuvants and the penicillin may be prepared and both materials administered simultaneously.
- 10 Where the product is to be administered intravenously, one of the adjuvants and penicillin may be included in a single ampul, and at the time of use dissolved in the menstruum, e. g., water or saline, and administered.

- 15 The adjuvants of particular importance from the standpoint of combination of effectiveness in blocking the tubular excretion of penicillin, low toxicity, and adequate absorption from the gastrointestinal tract, are 4' - carboxy-phenylmethanesulfonanilide (also known by the chemical name N-(benzylsulfonyl)-para- amino-benzoic acid), and its alkali metal salts, and p-carboxy-1-pentanesulfonanilide and its alkali metal salts.

The invention will be further illustrated but is not restricted to, the following composite products including penicillin and an adjuvant of the type embraced by the above general formula for administration by various routes:

- 30 *Example I.—Compressed tablet with penicillin.*—100,000 grams of N-(benzylsulfonyl)-para-aminobenzoic acid and 16,000 grams of lactose are mixed and wetted with sufficient water to permit its ready granulation in the usual way. 6749 grams of crystalline penicillin sodium (1630 units per mg.), 2651 grams of dried cornstarch, 600 grams karaya gum powder, 2800 grams talc, and 1200 grams calcium stearate are mixed together under atmospheric conditions controlled at 10% relative humidity at 21° C. and, under the same conditions, mixed with the granulation and tableted with one-half inch die standard curvature punches, yielding 200,000 tablets of 0.65 gram each and each containing 50,000 units penicillin (plus 10% excess).

- 35 *Example II.—Compressed tablet with penicillin and magnesium trisilicate.*—100,000 grams of N-(benzylsulfonyl)-para-aminobenzoic acid, 3000 grams magnesium trisilicate, and 7000 grams lactose are mixed and granulated as before described. Under atmosphere controlled as in the preceding example 3375 grams of the same crystalline penicillin sodium, 2625 grams of dried cornstarch, 500 grams karaya gum powder, 2500 grams talc, and 1000 grams calcium stearate are mixed and then mixed with the granulation, and this mixture tableted as before yielding 200,000 tablets of 0.6 gram each and each containing 0.5 gram of the compound and 25,000 units penicillin (plus 10% excess).

- 40 *Example III.—Dry filled capsule with penicillin.*—Under atmosphere controlled as in the preceding examples, 25 kilos of N-(benzylsulfonyl)-para-aminobenzoic acid, 850 grams of crystalline penicillin sodium (as used above), and 150 grams of dried corn starch are intimately and uniformly mixed, and the mixture filled into capsules, yielding 50,000 capsules, each holding 0.52 gram of mixture containing 0.5 gram of compound and 25,000 units penicillin (plus 10% excess).

- 45 *Example IV.—Dry filled capsules with penicillin.*—As in the preceding example, 25 kilos of N-(benzylsulfonyl)-para-aminobenzoic acid, 1690 grams of the same crystalline penicillin sodium, and 310 grams of dried cornstarch are intimately and uniformly mixed and encapsulated in the

same type and size of capsule, yielding 50,000 capsules, each holding 0.54 gram of mixture containing 0.5 gram of compound and 50,000 units penicillin (plus 10% excess).

Example V.—Dry filled capsule with magnesium trisilicate and penicillin.—Under atmosphere controlled as in Example I, 25 kilos of N-(benzylsulfonyl)-para-aminobenzoic acid, 850 grams of the same crystalline penicillin sodium, and 150 grams of magnesium trisilicate are intimately and uniformly mixed and encapsulated in the same size and type of capsule, yielding 50,000 capsules, each holding 0.52 gram of mixture and containing 0.5 gram of the compound and 25,000 units penicillin (plus 10% excess).

Example VI.—Dry filled capsule with magnesium trisilicate and penicillin.—Under atmosphere controlled as in Example I, 25 kilos of N-(benzylsulfonyl)-para-aminobenzoic acid, 1.69 kilos of the same crystalline penicillin sodium, and 310 grams of magnesium trisilicate are intimately and uniformly mixed and encapsulated in the same size and type of capsule, yielding 50,000 capsules, each holding 0.54 gram of mixture and containing 0.5 gram of the compound and 50,000 units penicillin (plus 10% excess).

While each of the individual examples has been illustrated with the respectively disclosed adjuvant, the latter in each of them may be replaced by any other suitable compound falling within the scope of the general formula, for example, any of those compounds specifically named above.

Example VII.—Soft elastic capsule with penicillin.—Under atmosphere controlled as in Example I, 1.69 kilos of the same crystalline penicillin sodium are homogeneously dispersed in 48.31 kilos of corn oil and 50 kilos of N-(benzylsulfonyl)-para-aminobenzoic acid similarly dispersed in the oil, and the resulting composition encapsulated in known manner in soft, elastic, sheet gelatin, hermetically sealed capsules, yielding 100,000 capsules, each holding one gram net of the composition and containing 0.5 gram of the compound with 25,000 units penicillin (plus 10% excess).

Example VIII.—Soluble elastic capsule with penicillin and magnesium trisilicate.—Under atmosphere as controlled in Example I 1687 grams of the same crystalline penicillin sodium, 7313 grams of magnesium trisilicate, and 50 kilos of N-(benzylsulfonyl)-para-aminobenzoic acid are intimately and uniformly mixed and the mixture homogeneously dispersed in 41 kilos of corn oil, and the dispersion encapsulated in the same type of soluble elastic capsules as in the preceding examples, yielding 100,000 capsules each holding one gram net of the dispersion and containing 0.5 gram of the compound with 25,000 units penicillin (plus 10% excess).

While in each of the preceding examples of soluble elastic capsules a respective individual adjuvant was included, any other of the adjuvants named above may be similarly included by substituting the same quantity of it in any of the particular examples.

Example IX.—Flame-sealed ampul filled with penicillin.—12.5 kilos of N-(benzylsulfonyl)-para-aminobenzoic acid are stirred into very nearly 30 liters of sterile, pyrogen-free distilled water and 1795 grams of sodium hydroxide are added to aid in its dissolution. Then 390 grams of monopotassium phosphate are added and, under atmosphere conditions as in Example I, 169 grams of the same crystalline penicillin sodium

are added and stirred into solution and sufficient water added to bring the total volume of solution to 30 liters. 12 cc. of this solution are then filled into each of the required number of 20 cc. total volume ampul-vials. The contents of the vials are then quickly frozen by rotating them in a bath of methyl "Cellosolve" chilled with "Dry-Ice" to -70° C., and desiccated under high vacuum for 48 hours by the method and apparatus as in United States Patent No. 2,353,985, and rubber stoppers inserted in the neck of each of the containers while the vacuum is still being maintained. The vacuum is then broken and the containers removed from the apparatus and the extension of the glass neck beyond the top of the stoppers is flame-sealed. The contents of the flame-sealed ampul-vial is then restored with sterile, pyrogen-free, distilled water shortly before the product is to be used. When thus restored to 20 cc. liquid volume, the resulting solution is buffered at pH 7.4 and contains 100,000 units penicillin (plus the 10% excess) and 25% of the compound. Of course, the product may be prepared in vials similar to those used for penicillin, i. e., rubber stoppered vials, or other containers, if desired.

Example X.—Ampul oil suspension with penicillin.—3 kilos of USP white wax are mixed into 35.127 kilos of purified peanut oil heated sufficiently to melt and permit homogeneous dispersion of the white wax. While this mixture is still sufficiently liquid, and under atmosphere conditions as in Example I, 10 kilos of N-(benzylsulfonyl)-para-aminobenzoic acid and 1873 grams of calcium penicillin (734 units/mg.) are added and the mixture stirred to homogeneity. Each cc. of the resulting oil suspension contains 25,000 units of penicillin (plus 10% excess) and 0.2 gram of the compound. It is put up in flame-sealed ampuls containing suitable volume of the suspension which is as stable as the ordinary penicillin in peanut oil preparation. Other types of containers, such as the ordinary ampul vials, or vials such as are used with penicillin, may be used.

While each of the preceding examples of particular ampul preparations contains its respective specific adjuvant, each of them may be prepared with any of the other adjuvants falling within the scope of the general formula, above.

In the various Examples I through X where no particular specifications for individual ingredients are given, it is understood that there is used such quality of the various ingredients as is suitable for incorporation in pharmaceutical preparations.

This application is a division of our application Serial Number 695,040, filed September 5, 1946, now abandoned, and Serial Number 761,153, filed July 15, 1947, now Patent Number 2,531,367.

What is claimed is:

1. A composite product prepared for a therapeutic use, said product including penicillin and an adjuvant having the general formula:

in which R_1 is selected from the class consisting of hydrocarbon and dialkyl ether radicals having a total of from 3 to 7 carbon atoms, phenyl, aminophenyl, nitrophenyl, halophenyl, and benzyl, and R_2 is selected from the class consisting of benzene and thiazole, the adjuvant constituent of said composition upon administration functioning substantially to block the excretion of

penicillin by interfering with the normal functioning of the transport mechanism of the kidney tubules.

2. A composite product prepared for a therapeutic use, said product including penicillin and the adjuvant N-(benzylsulfonyl)-p-aminobenzoic acid, the adjuvant constituent of said composition upon administration functioning substantially to block the excretion of penicillin by interfering with the normal functioning of the transport mechanism of the kidney tubules. 10
